FALSE TWIST TUBE FOR USE IN PREPARATORY AND SPINNING MACHINES

Joseph Noguera, Manchester, England, assignor to Casablanca High Draft Company Limited, Manchester, England, a British company

Application March 29, 1946, Serial No. 658,136
In Great Britain April 13, 1945

7 Claims. (Cl. 57—128)

1

This invention relates to false twist tubes for use in certain preparatory and spinning machines, more particularly in compound drafting machines wherein the tube is mounted between two consecutive drafting arrangements. The purpose of the false twist tube is to twist the strand as it passes from one drafting arrangement to the next, the material being usually subjected to a certain amount of draft while receiving the false twist from the tube.

There are two common types of false twist tube. According to the first, a nip is formed on the material as it passes between the two co-operating prongs of a spring, or between a spring and a fixed part of the tube, while according to the second, the twist is imparted to the material by causing it to follow a zig-zag path. The invention is concerned with the second type of tube which has the advantage, *inter alia*, of being easier to thread.

The necessary zig-zag path is usually given to the strand by causing it to pass through an inclined groove formed in a head located a short distance away from the exit end of the tube, the two parts of said zig-zag path thus consisting of the inclined groove and the path between the forward end of said groove and the exit of the tube. The material is therefore caused to crank about the forward end of said slot and the amount of twist imparted to the strand depends upon the extent of this cranking action. It will readily be understood that for a given size of groove, the cranking effect and therefore the twisting efficiency, will be greater the greater the thickness of the strand, which is a disadvantage especially when dealing with strands composed of comparatively short fibers, such as cotton where the action of the false twist tube should be as nearly correct as possible for each thickness of strand on account of the ease with which the material stretches. The only solution would be to have different tubes for different thicknesses of material but in practice this would be very inconvenient. Another disadvantage of this type of tube is that the efficiency of the twisting action is directly proportional to the tension of the strand, with the result that strands which have already become slightly over-twisted and therefore taut will tend to have the twist accentuated while strands which are in-

sufficiently twisted and therefore slack will be less intensely twisted.

The present invention seeks to provide a false twist tube of the kind described wherein the intensity of the twisting action is inversely proportional to the tension of the strand, and which will impart a uniform amount of twist to strands of widely different thicknesses.

In accordance with the invention there is provided a false twist tube wherein an abutment is provided over which a strand passes in proceeding towards the outlet of the tube, and wherein means is arranged to bear resiliently upon the strand at a point intermediate the abutment and the outlet of the tube whereby the strand is caused to follow an appropriate zig-zag path.

For a better understanding of the nature of the invention and the manner in which the same may be carried into effect, reference will now be made to the accompanying drawings in which:

Figure 1 is a longitudinal section through a known type of false twist tube.

Figures 2 and 3 are sectional details of the false twist tube shown in Fig. 1, with strands of different thicknesses shown therein.

Figure 4 is a longitudinal section through a false twist tube produced in accordance with the invention.

Figure 5 is an end view of the tube shown in Figure 4.

Figure 6 is a side elevation of a detail of one end of the tube shown in Figure 4, and

Figures 7, 8 and 9 are sectional details of the tube shown in Figure 4, with various thicknesses of strand shown in their working positions.

Referring first to the known false twist tube shown in Figs. 1 to 3 it will be observed that the tube essentially comprises a body 1 of hollow cylindrical form provided with an internal transverse guide portion 2. There is an inclined guide-way 3 therein which is adapted to lead a strand 4 in zig-zag fashion towards the outlet 5. In use the false twist tube is rotated about its axis and the strand 4 therein has a twist imparted to it. Figs. 2 and 3 show the same false twist tube as in Fig. 1 when threaded with strands of different diameters. It is clear that the thick strand 6 of Fig. 2 bears upon the inclined guide-way at points A and B and also at the point C

upon the outlet. Similarly, the thin strand 7 (Fig. 3) bears upon these same points but it will be observed that in the case of the strand 6 there is a much greater degree of cranking produced by the inclined guideway. The strand 7 is almost undeflected by the inclined guideway for the reason that the strand is thin and the points A, B and C are almost in line. Thus it will be appreciated that with the known false twist tubes their effectiveness will depend to some extent upon the diameters of the strands threaded therein. It will also be appreciated that the effect of the known false twist tubes will be undesirable with regard to varying tensions in a strand. Thus for example in the case of the strand 7 of Fig. 3, when the strand is relatively slack and does therefore require to be further twisted, in fact the amount of twist imparted thereto will be less than that which would have been imparted if the strand had been tauter. On the other hand when the strand 7 is very taut due to over-twisting the tendency will be to impart yet further twist to the strand.

Referring now to Figs. 4 to 9 of the drawings, it will be seen that the false twist tube of the invention is generally of the same external appearance as the known tube, comprising a cylindrical body 10 with an outlet 11. Within the hollow of the cylindrical body 10 there is an abutment 12 (Figs. 4, 5 and 6) over which the strand 13 passes. The abutment 12 has a transverse linear face working against the strand 13 but there is a central recess which locates the strand. The strand is held in contact with the abutment 12 by a leaf-spring 14 secured as at 15 to the internal walls of the cylindrical member 10. As will be seen from Fig. 4, the free end of the leaf spring 14 is cranked and is turned back on itself as at 16 to form a smooth working edge for contact with the strand 13. From Figs. 5 and 6 it will be observed that the outlet end of the tubular member 10 is on either side formed with cut-out portions 17 and 18 through which the working end of the leaf spring 14 projects. The cut-out portion 17 opens into a longitudinal passageway 17A formed in the side of the cylindrical body member 10, and opens also, by means of a passage 19, into the feed outlet 11. As indicated in Fig. 5, the longitudinal passageway 17A passes obliquely as at 17B through the rim 20 formed externally upon the cylindrical body member 10. It will be noted from Fig. 5 that the free end 16 of the spring 14 flares outwardly towards the extremity thereof and such extremity is bent so that a concave surface is presented to the strand 13 when the same is contacted by the spring.

It is a matter of extreme simplicity to thread a strand into the false twist tube described above, since whilst the tube is held in the left hand, a finger of the left hand may be employed to raise the leaf spring away from the abutment 12. The strand may then be entered into the slot 17B and from thence into the leadway 19 and into the outlet 11 itself. In bringing the strand to the outlet it is passed between the end of the raised leaf spring and the abutment 12 so that when the spring is released it will assume the position indicated in Fig. 4 with reference to the strand.

Figures 7, 8 and 9 show various thicknesses of strand in a false twist tube of the invention. In Fig. 7 it will be observed that the strand 21 is of relatively great diameter. The leaf spring 14 adjusts itself to accommodate the strand 21

and exerts a pressure thereon which will be substantially the same as the pressure exerted on the thinner strand 22 of Fig. 8, because the leaf spring 14 is of relatively great length and the extra deflection involved will not noticeably increase the reaction tension in the spring. In both Figs. 7 and 8 the strands 21 and 22 are fairly taut indicating that no great degree of twist should be imparted to them. It will be observed that in both cases the degree of cranking of the strand produced by the spring blade 14 is not very great. This may be seen by comparison with Fig. 9 where it is supposed that a medium size strand 23 is being dealt with, this strand being somewhat more slack. Because the tension is not so great in the strand 23 it is bent to a much greater extent out of line and accordingly increased twist is imparted thereto tending to increase the tension in the strand. In this way the desired control of the strand is obtained.

It has been indicated above that the degree of cranking imparted to a strand determines the twist imparted thereto. The expression "degree of cranking" is to be read as referring not only to the variation of the crank radius but also to the variation of the angle of the zig-zag path followed by a strand. Thus a greater degree of cranking and hence a more effective impartation of twist could be obtained by causing a strand to follow a sharper zig-zag path whilst maintaining the same crank radius.

I claim:

1. A false twist device for use in preparatory and spinning machines for textile fibres comprising a false twist tube, an inlet and outlet respectively at opposite ends of said tube, an abutment within said tube over which the fibre strand passes in proceeding from the inlet towards the outlet, and means, bearing resiliently upon the strand at a point intermediate said abutment and said tube outlet, whereby said strand is caused to follow a zig-zag path.

2. In drafting mechanism for textile fibres, a false twist device comprising a false twist tube, a feed inlet and outlet respectively at opposite ends of said tube, a fixed abutment within said tube, over which the fibre strand passes in proceeding from the inlet towards the outlet, and a spring bearing resiliently upon the strand at a point intermediate said abutment and said tube outlet, whereby the strand is caused to follow a zig-zag path.

3. A false twist device for use in drafting mechanism for textile fibres comprising a false twist tube, through which the fibre strand passes during the drafting process, an inlet and outlet at opposite ends of said tube, an abutment within the tube over which the fibre strand passes in proceeding through the tube, and a leaf spring mounted inside the tube with one end secured adjacent the inlet and with the other end free and bearing resiliently upon the strand at a point intermediate said abutment and said outlet, whereby said strand is caused to follow a zig-zag path.

4. A false twist device as claimed in claim 3 further comprising a bent portion at the free end of the leaf spring extending towards and beyond the inner edge of the abutment.

5. A false twist device for use in preparatory and spinning machines for textile fibres comprising a false twist tube through which the fibre strand passes, said tube having cut-away portions adjacent one end, a feed outlet between said cut-away portions, a feed inlet at the opposite end

of the tube, an abutment within said tube over which the fibre strand passes in proceeding from the inlet towards the outlet, and a leaf spring mounted within said tube and extending over the greater part of the length of the tube, said spring being attached at one end adjacent said inlet with the other free end partially protruding through said cut-out portions and bearing upon the strand between said abutment and said outlet, said strand being thereby caused to follow a zig-zag path.

6. A false twist device as claimed in claim 5 further comprising a longitudinal passageway in one side of the tube into which one of said cut-out portions opens, said cut-out portion also open-

10

15

ing into the outlet of the tube whereby threading is facilitated.

7. A false twist device as claimed in claim 3 further comprising a bent back tip on the free end of the leaf spring which presents a smooth working edge for contact with the strand.

JOSEPH NOGUERA.
